FIG. 1 is a perspective view from the front-right-top side of the docking station for a rechargeable lantern showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1; and,

FIG. 8 is front-right-top perspective view of the design shown in FIG. 1 with a rechargeable lantern shown in dotted line mounted in the docking station.

The broken lines in FIG. 7 are included for the purpose of illustrating a portion of the station that forms no part of the claimed design. The broken lines representing the lantern in FIG. 8 are included for the purpose of illustrating environmental structure only and form no part of the claimed design.
